CLAIM

The ornamental design for a display screen or portion thereof with graphical user interface as shown and described.

DESCRIPTION

The FIGURE is a front view of an embodiment of the claimed design of a display screen or portion thereof with a graphical user interface.

The outermost broken lines in the FIGURE illustrate a display screen or portion thereof and form no part of the

(Continued)

claimed design. The other broken lines in the FIGURE illustrate portions of the graphical user interface that form no part of the claimed design.
